UNITED STATES PATENT OFFICE.

THOMAS J. SMITH, OF AKRON, OHIO, ASSIGNOR TO THE FIRESTONE TIRE AND RUBBER COMPANY, OF AKRON, OHIO, A CORPORATION OF OHIO.

APPARATUS FOR UNWRAPPING INNER TUBES.

Original application filed April 25, 1919, Serial No. 292,640. Divided and this application filed September 24, 1925. Serial No. 58,467.

This invention, forming part of a combined unwrapping and stripping apparatus as set forth in application Serial No. 292,640, filed April 25, 1919, of which this application is a division, relates to an apparatus for use in unwrapping inner tubes on mandrels on which they are cured, and it is the object of the invention to perfect an apparatus which will facilitate the unwrapping of the tubes.

This and other objects will be apparent as the description proceeds and it will be noted that the invention is not restricted to the details shown, but may be modified in a variety of ways.

In the drawings:

Figure 1 is an end elevation of the apparatus;

Figure 2 is a plan view;

Figure 3 is a front elevation;

Figures 4 and 5 are detail views showing the construction of one of the overhead or transfer rails.

It will be understood that inner tubes for pneumatic tires are built up on mandrels and then wrapped tightly with one or more spiral wrappings of cloth before being placed in the vulcanizer. After being cured, the cloths are unwrapped and the tube is stripped from the mandrel by being peeled off in stocking fashion, air under pressure being used in this operation as is well understood by those skilled in the art.

In the drawings, there is shown one form of my invention in which 1 represents a series of standards on uprights which support the various parts of the apparatus. Longitudinally of the framework is secured a pair of rails 2, on which are arranged to be received the supporting wheels 3 of the cradle or carriage 4 in which the tubes are stacked and placed in the vulcanizer. On the lower portion of the carriage is arranged a stationary toothed rack 5 in which the mandrels 6 of the lower row are supported, and between each row of tubes are placed undulating separating bars 7 which hold and separate the tubes in the manner shown in Figure 1.

From the standards 1 extend a set of diagonal bars 8, arranged in pairs at the ends of the machine, each pair being joined by brace rods 9. On the rods is supported at

each side of the apparatus a bracket 10, the upper side of which is arranged with two box-like flanges 11, open at the top and partially enclosing a pair of rollers 12 rotatably mounted on pins 13 and designed to support the mandrels as they are unwrapped. The wrapper from the two mandrels is shown at 14 and is wrapped around a receiving stick or pole 15. The ends of this pole are formed with bearing pins and are received in the open ends of levers 16 pivoted at 17 on a bracket 18 which is secured to the framework. In the upper side of the bracket 18 is rotatably mounted a drive roll 19 extending across the length of the machine and which is driven at a high rate of speed by a pulley 19' and belt 20 from a motor or other source of power 21. A spring 22 is attached to the lower end of the lever 16 and to any convenient point and holds the pole 15 against the drive roll, so that when the end of the wrap is passed between the pole and the drive roll, it will wrap on the pole, the mandrel rotating on the rollers 12. Two mandrel holders are provided so that two tubes can be unwrapped at the same time and this number might be increased if found practicable.

On the side opposite the diagonal bars 8 are arranged a pair of bars 23 which extend at an angle to a point opposite the bracket 10 and then project upwardly for a distance approximately equal to the height of the pile of tubes, usually carried on the cradle 4. To the upper end of the bars 23 is secured a frame-work indicated by the numeral 24 which supports a trackway 25 composed of a series of rails 25, which incline toward the stripping side of the apparatus being provided with stop 26 which will hold a supply of unwrapped tubes ready to be stripped.

The rails are shown in detail in Figures 4 and 5 and are preferably formed of bars 27 hooked over the frame-work at one end and bolted in place at the other. These bars are covered with a rubber tubing 28 which protects the surface of the inner tube. It will be seen that the space limited by the bars 23 and framework 25 is large enough to hold a supply of tubes on the cradle and the workmen may remove the mandrels from the pile over the brackets 10.

The stripping apparatus is located on the side of the apparatus opposite the unwrapping device and is supported by the bars 23 on brackets 29. The stripping implements comprise a table or shelf 30 supported on the brackets and provided at one end with a supporting roller 31 and an abutment 32 against which the mandrel may be placed. A pipe for air under pressure is located at any suitable point, being shown at 33 in Figure 1.

The operation of the device will be readily understood. The tubes, as they are received from the heaters in the cradle 4, are rolled into place in the center of the apparatus as shown in Figure 1. The unwrappers remove the mandrels and place each one on one side of the supporting rollers 12. The end of the wrapper is then pulled off a short distance and inserted between the drive roller 19 and the pole 15. The roller 19 is driven continuously and at a high rate of speed so that the wrapper is quickly unwound from the tube. While one mandrel is being unwrapped, a second mandrel may be removed from the cradle, placed on the unoccupied set of rollers 12 and unwrapped at the same time.

After the wrapping is all removed, the mandrels are placed on the tracks 25 along which they roll until they strike the stop 26. The stripper operating on the opposite side of the machine removes the mandrels and places them on the shelf 30 where they are stripped.

It is apparent that changes and modifications may be made in the exact form shown in the drawings, and this patent is not limited to details as shown, but may be al-

tered within the scope thereof without departing from the spirit of the invention or sacrificing any of its benefits.

What is claimed is:

1. In an apparatus for unwrapping tubes, a framework, means on said framework for supporting wrapped tubes on mandrels, a set of revoluble rollers to support a mandrel, and a roller extending across the apparatus adjacent the support adapted to draw the wrapping from the tubes. 50

2. In an apparatus for unwrapping tubes, a framework, means on said framework for supporting wrapped tubes on mandrels, a plurality of sets of revoluble rollers to support a plurality of mandrels, and a roller extending across the apparatus adjacent the mandrel supports adapted to draw the wrappings from the tubes. 55

3. In an apparatus for unwrapping tubes, a framework, means on said framework for supporting wrapped tubes on mandrels, a set of revoluble rollers to support a mandrel, a roller extending across the apparatus adjacent the support, means for holding a pole to receive the wrapping from the tubes in contact with the said roller, and means for rotating said roller. 60

4. In an apparatus for unwrapping tubes, a framework, means on said framework for supporting wrapped tubes on mandrels, a plurality of sets of revoluble rollers to support a plurality of mandrels, a single roller extending across the apparatus adjacent the supports, means for holding a pole to receive the wrapping from the tube in contact with said roller, and means for revolving said roller. 70 75
